DUMP WAGON DOOR

Original Filed April 17, 1928

UNITED STATES PATENT OFFICE

JAMES D. BENBOW AND JAMES B. GREEN, OF AURORA, ILLINOIS, ASSIGNORS TO WESTERN WHEELED SCRAPER COMPANY, OF AURORA, ILLINOIS, A CORPORATION OF ILLINOIS

DUMP WAGON DOOR

Original application filed April 17, 1928, Serial No. 270,645. Divided and this application filed February 14, 1929. Serial No. 339,822.

The present invention relates to dump wagons, having particular reference to such dump wagons of the bottom dump type, which employ one or more bottom doors or gates adapted to be swung down in the dumping operation, and the principal object of the present invention is the provision of a new and improved door structure for wagons of this kind.

10 This application is a division of our pending application Serial No. 270,645 filed April 17, 1928, now Patent No. 1,706,099, granted March 19, 1929, to which application reference is here made for the structural de-

15 tails of the complete dump wagon.

Briefly, however, that patent discloses a dump wagon comprising a frame supported on an arched rear axle upon which are mounted a pair of self-laying track units, commonly known as caterpillar treads. The body of the dump wagon is divided into fore-and-aft parts by a centrally located partition running transversely of the frame and body. The bottom of each of these compartments is 20 closed by two doors of the type forming the subject of the instant application. Suitable locks and release mechanisms are provided for raising and lowering these doors in the manner best understood from a reading of our prior patent.

25 In the drawing, a preferred embodiment of the door structure is shown to acquaint those skilled in the art with the invention.

Figure 1 is a plan view of a completely 30 assembled door;

Figure 2 is a sectional view of Figure 1, taken along the line 2-2 looking in the direction of the arrows;

Figure 3 is a detailed view of the hanger 35 mounting, taken along the line 3-3 of Figure 1, looking in the direction of the arrows;

Figure 4 is a detailed view of the door taken along the line 4-4 of Figure 1, looking in the direction of the arrows and showing also a part of the body upon which the door structure is mounted.

In these figures, the reference numeral applied correspond to the reference numerals applied to the corresponding parts in the prior patent, to thereby facilitate cross ref-

erence between this application and its predecessor.

Referring to the drawing in more detail, it will be seen that the door comprises a plurality of laterally disposed Z bars 81, which form a frame upon which the door is built. The face of the door comprises the sheet metal member 82, which rests on one of the flanges of the Z bars and which has its edges rolled over the ends of the Z bars 81 and riveted to the face of the opposite flanges of the Z bars. In this manner, the edges of the plate 82 are formed into channels 83, which stiffen the door.

The upper flanges of the Z bars afford attaching surfaces to which the top portion of the plate 82 is riveted at closely spaced intervals. The lower flanges of the Z bars also afford attaching surfaces to which the inwardly bent lower edges of the channel 83 are secured.

The two bars at the ends of the door have tubular guide brackets 84 secured thereto adjacent to the swinging edge of the door, through which brackets passes the hoisting chain 101, which raises the door into engagement with the body of the wagon. The intermediate Z bars have openings 84' provided in the vertical webs thereof in alignment with the guide brackets 84, to form a continuous 75 passageway through the door for the chain 101.

It will be noted that the downwardly and inwardly bent channel portion 83 at the swinging edge of the door substantially embraces the hoisting chain 101 around the edge and underside of the door, thereby affording a protective box-like runway for the chain and preventing the entrance of dirt to the chain, if this edge of the door should drag 80 in the dirt during the dumping operation of the wagon.

Secured to the outer edge of the door at longitudinally spaced points along its length are hinge brackets 85, the horizontal portions 85' of which extend through openings 83' in the channel 83, and are rigidly secured to the bars 81 of the door by rivets.

At the points where the hinge brackets enter the door, the Z bars are grouped in

100

pairs, with the upper flanges of each pair disposed substantially edge to edge, thereby defining a channel shaped socket for receiving the inner end 85' of the hinge bracket. Attaching portion 85' of the latter is also of channel shaped section, the side flanges thereof being riveted to the webs of the Z bars, and the web of the attaching portion 85' being riveted through the top flanges of the 10 Z bars and through the door plate 82. Thus, each hinge bracket has a staunch, durable attachment to the door. The outer portion of each hinge bracket is inclined upwardly and inwardly and is apertured to provide a 15 hinge eye 86, as best seen in Figure 2. Each eye 86 engages around a bracket 87, which has its lower end secured to the web of the side channel 16 of the body of the wagon, as seen in Figure 4, and having its upper end secured 20 to the upper end of channel 16, which latter connection is not shown herein.

It will be evident that the foregoing hinge connection permits a certain amount of play of the door relatively to the body of the 25 wagon. The doors in their dump position will tend to hang with their lower edges disposed under the frame of the wagon, but the doors are free to swing outwardly to the sides of the frame in clearing themselves of the pile 30 of dirt dumped from the wagon. Moreover, the mounting of the eyes 86 on the brackets 87 permits the door to move upwardly and downwardly, when in their dumped position so that they can clear themselves from the 35 dumped pile or other obstructions, as the wagon is being drawn away, after dumping. In their closed position, the doors are disposed substantially flush with the lower edges of the side channels 16, as shown in Figure 4. 40 Thus, it will be seen that the door disclosed in this application lends itself particularly well for use with a dump wagon. It is strong enough to withstand the shock of dropping large quantities of dirt and rock 45 on it, and is mounted with sufficient flexibility to permit its being dragged over a freshly dumped pile of dirt, without injury to itself.

In the preferred embodiment of the door shown in the drawing by way of example, the Z bars, door plates, chain guides, and hinges are riveted together. Obviously, welding or any other desired form of attachment could be substituted for riveting, without departing from the teachings of the invention. 50

Nor is the invention limited to the use of Z bars as channels or any other structural shape may be substituted therefor.

Having thus complied with the statutes and shown and described a preferred embodiment of our invention, what we consider new and desire to have protected by Letters Patent is pointed out in the appended claims.

What is claimed is:

1. In a door for a dump vehicle, the combination of a sheet of metal, a plurality of

bars of structural shape having webs and flanges, said bars disposed in parallelism upon said sheet of metal, said sheet having the margins thereof folded transversely over the ends of said bars to form reinforcing flanges 70 for the edges transverse to the bars, said bars having openings through the webs thereof, said openings being disposed in a line parallel to one of the folded edges, and a chain passing loosely through said openings. 75

2. In a door for a dump vehicle, a plurality of parallel bars of structural shape having flanges and webs, a sheet of metal having opposite edges folded over the ends of the bars and secured thereto, said bars having openings in their webs adjacent one edge of the door, and guides secured to the bars at the 80 ends of the door in line with said openings for guiding a tension member through said openings. 85

3. In a door for a dump vehicle, a plurality of parallel bars of structural shape having flanges and webs, a sheet of metal having opposite edges folded over the ends of the bars and secured thereto to form reinforcing 90 flanges, openings in the bent over portion of the sheet at one edge of the door, and hinge members having shanks extending through said openings and being provided with flange and web portions for nesting with the flanges 95 and webs of the adjacent bars, said hinge members and said bars being secured together.

4. A dump door comprising a frame structure, a plate secured to the upper side of said frame structure, hinge means for pivotally connecting one edge of said door, and a flexible hoisting member having operative connection with the other edge of said door, said hoisting member extending through the door substantially from end to end thereof adjacent to said latter edge, the marginal portion of said plate at said latter edge being bent partially around said hoisting member to form a protective boxing therefor against 105 the entrance of dirt. 110

5. A dump door comprising a plurality of transversely extending bars, a plate secured to the upper sides of said bars and having its edges bent downwardly around the ends 115 of said bars and under the same along the side margin of the door, and guide means carried by said door for guiding a hoisting chain extending longitudinally of the door between the ends thereof. 120

6. A dump door comprising a plurality of transversely extending bars of flanged cross section, a plate secured to the upper sides of said bars and having its lateral edges bent downwardly around the ends of said bars, and hinge members extending into the body 125 of the door and being secured directly to said bars.

7. A dump door comprising pairs of transversely extending bars of approximately 130

5 Z-shaped cross section disposed at longitudinally spaced points along the length of the door, a plate secured to the upper flanges of said bars having its lateral margins bent downwardly and inwardly around and under the ends of the bars, each pair of bars defining a channel shaped socket within the door, said plate having openings cut therein in line with said sockets at the hinge edge of the door, and hinge brackets extending through said openings and being secured within said sockets.

10 8. In a door for dump vehicles, a plurality of parallel Z bars, a plate disposed over the face of one of the flanges of said bars and having its edges bent over the ends thereof and attached to the face of the other flanges of the bars, to form a channel edge for the door, sockets formed by adjacent ones of said 15 Z bars placed with their flanges edge to edge, an aperture in said channel edge of the door opposite said sockets, and hinge brackets having channel shaped shanks projecting through said apertures into said sockets and 20 outwardly and upwardly extending ring portions formed integral with the shanks, the ends of said rings being disposed substantially in the plane of the edge of said door.

25 9. A dump door including a frame, a plate secured to the frame, hinge means for pivotally connecting one edge of the door, and flexible hoisting means extending substantially from end to end of the door through the frame adjacent the other edge, said plate terminating in a hood along the last mentioned edge to reinforce the frame and to substantially enclose the hoisting means against access of dirt.

30 10. A dumping door for a dumping vehicle comprising a plurality of transversely extending bars, a plate forming the load supporting surface of the door disposed over the upper sides of said bars and having a margin thereof folded downwardly across the adjacent ends of said bars and thence inwardly under the lower sides of said bars to form a channel shaped reenforcing portion along one side of the door, said inwardly bent flange portion of the plate being secured to the under sides of said bars, said channel shaped reenforcing portion having spaced openings therein, hinge members having attaching shank portions extending through said openings and secured to the door at points inwardly of said openings, and guide members fastened to the door adjacent to the other margin thereof for receiving flexible hoisting means adapted to raise the door to closed position.

35 11. A dumping door for a dumping vehicle comprising a plurality of transversely extending bars, a plate forming the upper surface of the door extending over the upper sides of said bars and having two opposite edges thereof folded downwardly across the

40 ends of said bars and thence inwardly under the lower sides of said bars to form channel shaped reenforcing portions along two margins of the door, said inwardly bent flange portions of the plate being secured to the under sides of said bars, hinge members disposed in spaced relation along the channel shaped reenforcing portion at one margin of the door and having attaching portions secured to said plate, and means secured to the door adjacent to the other margin thereof for establishing operative connection with a flexible hoisting member adapted to raise the door to closed position.

45 In witness whereof we hereunto subscribe our names this 11th day of February, 1929.
